PARACHUTE PACK CONTAINER

Francis McCarroll, United States Navy

Application September 26, 1938, Serial No. 231,773

4 Claims. (Cl. 244—148)

(Granted under the act of March 3, 1883, as
amended April 30, 1928; 370 O. G. 757)

This invention relates to a parachute pack container and has for an object to provide an improved container flap opening mechanism which will operate more quickly and more certainly than the present conventional type of flap opener.

A further object of this invention is to so arrange the opening mechanism of a parachute pack container flap that there will be a positive opening action when the rip cord has been pulled, even though a long period of time may have elapsed since the parachute was packed in the container.

Still a further object of this invention is to eliminate the conventional snap fasteners used for holding the end of the protector part of the flap in protecting position yet make it possible for the cones, grommets and rip cord locking pins to be readily accessible for inspection.

Still a further object of this invention is to provide a parachute pack container flap opening mechanism which will open the container by removing the flap by a rolling motion positively lifting the grommets from the cones, rather than pulling them against the cones, as necessary with the present mechanism, which present mechanism often causes the flap to hesitate in opening, and sometimes even fails to open, particularly if the pack has been unopened for a considerable period of time.

With the foregoing and other objects in view, the invention consists in the construction, combination and arrangement of parts hereinafter described and illustrated in the drawing, in which Fig. 1 is a top plan partly X-ray view of a parachute pack container flap with the opening mechanism of this invention therein.

Fig. 2 is a sectional view on line 2—2 of Fig. 1; and

Fig. 3 is a view similar to Fig. 2 just after the initial opening step has commenced.

There is shown at 10 a parachute pack container having the rip cord conduit 11 through which passes the rip cord 12 having the rip cord pins 13 extending through eyes 14 of the cones 15 secured to the inner flap 16 as by stitching 17, the parachute pack 18 being contained therewithin. The outer flap 20 is provided with grommets 21 adapted to pass over the cones 15, the grommets 21 also serving for securing a patch flap 22 to the outer flap 20, the patch flap 22 being folded back to form a protector flap 23. The customary side flaps 24 are each provided with tabs 25 having grommets 26 which fit over the cones 15 beneath the pins 13, the side flaps

24 being provided with opening elastics 27 and the usual hooks 28 to be secured to elastic anchorages or eyes 30 on the tabs 25. Similar elastics 31 with their hooks 32 are secured at one end to elastic anchorages or eyes 33 on the end of flap 16 and at the other end instead of being secured to the outer flap 20 or the patch flap 22, as customary, the hooks 34 are secured to elastic anchorages or eyes 35 which are secured to the inside of the protecting flap 23 adjacent the edge thereof, as shown.

In operation, when it is desired to inspect the rip cord pins 13 and cones 15 the protecting flap 23 may be raised against the resisting force of the elastics 31 sufficiently to allow the same 15 to be inspected, or, if desired, the hooks 34 are merely released from the eyes 35, allowing the protecting flap 23 to be raised without resistance.

When the parachute is operated in the customary manner by pulling the rip cord 12 through the rip cord conduit 11 the pins 13 will be withdrawn from the eyes 14 of cones 15, releasing the flap 20 and tabs 25 to the pull of their elastics 27 and 31. The elastic 31 being secured to the protecting flap 23 tends to lift the grommet 21 off the cones 15, likewise lifting the grommets simultaneously, providing a rolling action of the grommets off the cones rather than a sliding action of the grommets against the sides of the cones. The separation of the grommets from the cones and thus of the flaps from each other is therefore more positive and likewise somewhat quicker than is possible with the old style of opening devices, for the ends of the flap are pulled positively away from each other rather than in a sliding motion wherein the cone may provide an obstruction or separation.

Other modifications and changes in the proportions and arrangements of the parts may be made by those skilled in the art without departing from the nature of the invention, within the scope of what is hereinafter claimed.

The invention described herein may be manufactured and/or used by or for the Government of the United States of America for governmental purposes without the payment of any royalties thereon or therefor.

Having thus set forth and disclosed the nature of this invention, what is claimed is:

1. A parachute pack container flap-opening device wherein an upper flap has a grommet releasably secured by a rip cord pin extending through an aperture in a cone secured to a lower flap, the upper flap being also provided with a

- protecting flap folded over the grommet and cone and including elastic means anchored at one end to the lower flap, anchorage means for the other end of said elastic means secured to the protecting flap adjacent the end thereof.
5. 2. Means for opening a parachute-pack container overlapped flaps wherein the under flap is provided with an apertured rip cord pin receiving cone and the upper flap is provided with a grommet through which said cone extends to receive the rip cord pin, and a protecting flap secured to said upper flap and overlying the rip cord pin and cone, said means including opening elastics anchored at one end to the under flap 10 and at the other end adjacent the end of the protecting flap of the upper flap to lift the grommet from the cones in a rolling action.
15. 3. In a parachute-pack container having overlapped flaps secured together by a rip cord pin inserted through an apertured cone secured to the lower flap and extending through the upper 20

flap, means for quickly separating the flaps with a relatively rolling motion comprising an opening elastic, anchorage means for the elastic on the lower flap, and anchorage means for the elastic on the upper flap on the free end thereof extending beyond the securing cone.

4. In a parachute-pack container having overlapped flaps secured together by a rip cord pin inserted through an apertured cone secured to the lower flap and extending through the upper 10 flap, means for quickly separating the flaps with a relatively rolling motion comprising an opening elastic, anchorage means for the elastic on the lower flap, and anchorage means for the elastic on the upper flap on the free end thereof 15 extending beyond the securing cone, said free end being folded back to provide a protecting flap, said last mentioned anchorage means being located adjacent the end of said protecting flap.
